UNITED STATES PATENT OFFICE.

CHARLES D. HUNGATE, OF CAMP CREEK, VIRGINIA.

BAIL ATTACHMENT.

No. 874,681.

Specification of Letters Patent.

Patented Dec. 24, 1907.

Application filed May 3, 1907. Serial No. 371,707.

To all whom it may concern:

Be it known that I, CHARLES D. HUNGATE, citizen of the United States, residing at Camp Creek, in the county of Floyd and 5 State of Virginia, have invented certain new and useful Improvements in Bail Attachments, of which the following is a specification.

The present invention aims to provide a 10 novel form of bail attachment which can be readily applied to a milk jar or like receptacle and forms a convenient means for transporting the same from place to place.

The invention has for its further object 15 to design an attachment of this character which is simple and inexpensive in its construction and can be easily and quickly applied to the jar or removed therefrom as required.

20 For a full description of the invention and the merits thereof and also to acquire a knowledge of the details of construction and the means for effecting the result, reference is to be had to the following description and 25 accompanying drawings, in which:

Figure 1 is a perspective view showing the bail applied to the neck of a milk bottle. Fig. 2 is a similar view showing the bail attachment removed. Fig. 3 is an enlarged 30 detail view of the keeper.

Corresponding and like parts are referred to in the following description and indicated in all the views of the drawings by the same reference characters.

35 In general the invention embodies a clamping device which is in the nature of a band designed to extend around the neck of the bottle or receptacle to which the attachment is applied, and a bail having an operative 40 connection with the said band.

The numerals 1 designate the oppositely facing jaws of the clamp which are shown as approximately semicircular in form, although they may be given any desired shape 45 according to the nature of the receptacle in connection with which the attachment is to be employed.

Bell crank levers 2 are pivotally connected at the junction of their two arms to the 50 extremities of the jaws 1 as indicated at 3. One arm 4 of each of the bell crank levers 2 extends downwardly and the corresponding arms 4 upon opposite sides of the clamp are extended inwardly and loosely connected at 55 5. In order to draw the downwardly ex-

tending arms 4 toward each other and throw the jaws 1 of the clamp into engagement with the bottle neck spring members 6 are provided which connect each pair of the downwardly extending arms 4 and are preferably 60 secured to hook members 7 projecting outwardly therefrom. It will thus be apparent that in applying the clamp the jaws 1 can be forced apart against the tension of the spring 6 and that when the jaws are released the 65 same will be drawn into an operative position through the medium of the said springs. The opposite arms 8 of each pair of the bell crank levers 2 project outwardly in opposite directions and have the link members 9 piv- 70 oted to the extremities thereof.

A keeper 10 is loosely connected to the inner ends of each pair of the link members 9 and the said keepers form a means for connecting the hooked ends of the bail 11 to the 75 above described clamping device. This bail 11 is of the conventional construction and is shown as having the handle 12 applied thereto. In the specific construction of the keeper 10 it will be observed that the lower portion 80 thereof is bifurcated to receive the inner ends of the link members 9 which overlap each other and are pivotally mounted upon the pin 13 connecting the two arms of the bifurcation. When the keepers 10 are pushed 85 downwardly either through the medium of the bail 11 or by any other convenient means the link members 9 are drawn into alignment with each other and the bell crank levers 2 moved outwardly in such a manner as to 90 throw the jaws 1 away from each other. When in this position the clamping ring can be applied to the neck of the bottle or other receptacle and upon an upward force being exerted upon the keepers 10 the tension in 95 the springs 6 operates to draw the downwardly extending arms 4 of the levers 2 together and to throw the jaws of the clamp into a firm engagement with the said bottle neck.

Having thus described the invention, what is claimed as new is:

1. In a device of the character described, the combination of a clamping band, operating levers applied to the ends of the band, a 105 bail, and connecting means between the bail and the operating levers.
2. In a device of the character described, the combination of a clamping band, bell crank levers applied to the ends of the band 110

for drawing the same together, a bail, and connecting means between the bail and the bell crank levers.

3. In a device of the character described, 5 the combination of a clamping band, operating levers applied to the ends of the band for drawing the same together, link members connected to the operating levers, a bail, and connecting means between the bail and the 10 link members.

4. In a device of the character described, 15 the combination of a clamping band, bell crank levers applied to the ends of the band to draw the same together, the said bell crank levers having one pair of arms pivotally connected while the opposite pair extend outwardly in opposite directions, link members connected to the extremities of the second mentioned pair of arms, a bail, and connecting means between the bail and the said 20 link members.

5. In a device of the character described, 25 the combination of a clamping band, bell crank levers applied to the ends of the band, the said bell crank levers having one pair of

arms pivotally connected while the opposite pair of arms extend outwardly in opposite directions, link members loosely connected to the extremities of the second mentioned pair of arms, a keeper connected to the link members, and a bail applied to the keepers. 30

6. In a device of the character described, the combination of a clamp comprising a pair of oppositely facing jaws, bell crank levers pivotally connected to the ends of the jaws, 35 each pair of bell crank levers having corresponding arms extending downwardly and pivotally connected while the opposite arms project outwardly in opposite directions, link members loosely connected to the extremities of the second mentioned arms, a keeper connecting the inner ends of each pair of link members, and a bail applied to the keepers. 40

In testimony whereof I affix my signature in presence of two witnesses.

CHARLES D. HUNGATE. [L. S.]
